UNITED STATES PATENT OFFICE.

LOUIS L. DRIGGS, OF WASHINGTON, DISTRICT OF COLUMBIA, ASSIGNOR
TO THE DRIGGS-SEABURY ORDNANCE CORPORATION, OF SHARON,
PENNSYLVANIA, A CORPORATION OF PENNSYLVANIA.

PERCUSSION-FUSE.

No. 805,271.

Specification of Letters Patent.

Patented Nov. 21, 1905.

Application filed July 26, 1905. Serial No. 271,357.

To all whom it may concern:

Be it known that I, LOUIS L. DRIGGS, a citizen of the United States, residing at Washington, in the District of Columbia, have invented certain new and useful Improvements in Percussion-Fuses; and I do hereby declare the following to be a full, clear, and exact description of the invention, such as will enable others skilled in the art to which it appertains to make and use the same.

My invention relates to improvements in shell-fuses and in means for attaching the fuse to the shell; and it consists in certain improved means whereby the fuse may be readily attached to and removed from the shell when the latter is loaded without danger of accidental ignition of the bursting charge of the shell.

From time to time accidents have happened in removing the bursting charges from the shell, and in most of such instances the attendants, who alone might be able to completely explain the cause of the explosion, have been blown to pieces. Consequently the causes of such explosions are mainly deducible by theory only. It is generally supposed, however, that these explosions are caused by the sifting of fine powder-grains into the screw-threads between the fuse and its bouching, and that when the force requisite to unscrew the fuse is applied the friction on the fine powder-grains causes ignition, which is transmitted to the powder charge in the shell.

My present invention is intended to provide means whereby such accidents may be avoided.

Figure 1 shows a side elevation of a shell with the fuse protected according to my invention. Fig. 2 shows a central horizontal section of the device shown in Fig. 1, but on a larger scale, the fuse being shown in elevation. Fig. 3 shows a modification in which the interior mechanism of the fuse is removed and the fuse-stock itself remains permanently in the shell when the same is unloaded and re-loaded. Fig. 4 shows another modification adapted for use with heavier shell, in which the base-wall of the shell would necessarily be quite thick. Fig. 5 shows the fuse mounted in the point of the shell according to my invention; and Fig. 6 shows a section along the line 6 6 of Fig. 5 and looking to the right,

the end of the fuse-stock being shown in elevation.

Referring first to Figs. 1 and 2, A represents the shell. B represents the bouching screwed into the base of the shell and projecting slightly beyond the rear edge thereof. D represents the fuse, which is flanged, as at d, and the said flange fits in a recess b in the bouching. The bouching may be cut out in wake of the flange d, as indicated in dotted lines at b' in Fig. 2, so as to permit the fuse to be caught hold of by suitable nippers. E represents a spline-pin which projects into the bouching and into the fuse-stock and holds the fuse against turning in the said bouching. F represents a cap which is screwed on over the bouching and holds the spline-pin E in place and also prevents the fuse from dropping out of the bouching. It will be seen that by unscrewing the cap F and withdrawing the fuse from the bouching the powder charge in the shell may be removed and the shell may be unloaded and loaded again without the necessity of unscrewing the bouching, and thus exerting material pressure on any fine powder-dust that may settle in the screw threads. It will be evident that the fuse may be withdrawn with much less effort than would be required to turn a screw, and therefore the danger from ignition due to the accumulation of powder-dust around the fuse-stock and between it and the bouching may be minimized. Furthermore, a leather washer I may be placed beneath the flange d of the fuse-stock for the purpose of keeping out powder-dust.

In the form of device shown in Fig. 3 the tube K is screwed into the shell and in this tube is held the bottom plug L, which rests over the shoulders k at the bottom of the tube K. This plug L is perforated to permit the passage of the flame and is preferably covered with a thin cap of paper or the like (not shown) to prevent the entrance of fine powder into the opening; but this cap may be omitted, if desired. Above this plug and screwed or otherwise held against turning in the tube is the anvil M, to which are rigidly attached the spring-arms N, having clips n, which engage the neck p' of the plunger P, which plunger is provided with a firing-pin p, which firing-pin explodes the fulminate-cap m, when the

shell is arrested in its flight. As the shell spins the clips n are thrown outward by centrifugal force, as fully described in the patent to William H. Driggs, No. 419,143, granted January 7, 1890, thus allowing the collar p^2 to pass between these clips n and permitting the plunger to fly forward and strike the fulminate-cap. Over the base of the fuse-stock I screw the cap Q. In order to unload the shell, it will only be necessary to remove the screw-cap, to unscrew the anvil M and the parts carried thereby, take out the plug L, and a passage-way to the interior of the shell is provided.

In the form of device shown in Fig. 4 the fuse D slips into the bouching B', screwed into the base of the shell, over which bouching is screwed the cap Q', whose rear surface is flush with the surface of the shell. This modification is more especially adapted for use with heavy shell. A spline-pin E, similar to that shown in Fig. 2, is provided. A leather washer I, beneath the flange d of the fuse-stock, also serves to keep powder-dust from the screw-threads of the cap and bouching.

Referring now to Figs. 5 and 6, the nose of the shell A is shouldered, as at a , and screw-threaded, as at a' , and is also internally shouldered, as at a^2 . The screw-cap R is preferably in the ogival form, to conform to the normal contour of the shell, and is provided with screw-threads r' to engage the screw-threads a' , and when screwed home the shoulder r abuts against the shoulder a . Around the fuse D, beneath its flange d, is placed a washer of leather or like material I, which is compressed between the shoulders a^2 and the flange d when the screw-cap is home, and thus prevents the sifting of any fine powder past the head of the fuse-stock. The fuse-stock is held against turning in the shell by means of the spline-pin E, which locks it to the shell, as indicated in Fig. 6. The groove in the fuse-stock for this spline-pin is short, so that the spline-pin cannot drop out into the interior of the shell, and it is held against dropping out the other way by the screw-cap R. Slots a^2 may be provided to insert nippers for withdrawing the fuse.

It will be seen that in the device shown in Figs. 2, 4, and 5 the fuse may be withdrawn longitudinally after the screw-cap has been moved and that the threads of the screw-cap are protected against the sifting in of any fine powder, and the shell may be loaded or unloaded through the opening left by the fuse.

In the form of device shown in Fig. 3 the essentials of the fuse—to wit, the plunger and the anvil and the spring for holding them together—can be removed by unscrewing and then drawn longitudinally out of the gun, and

the screw-threads of the anvil are protected by the plug L and its cap.

It will be obvious that various modifications might be made to accomplish the same result as the herein-described apparatus which could be used without departing from the spirit of my invention.

Having thus described my invention, what I claim, and desire to secure by Letters Patent of the United States, is—

1. In an explosive shell, the combination with the shell-body, of a screw-cap held thereon, and a fuse mounted in said shell-body beneath said screw-cap, and removable longitudinally therefrom, with a spline-pin locking said fuse against turning in said shell-body and held in place by said screw-cap, substantially as described.

2. In an explosive shell, the combination with the shell-body, of a screw-cap held thereon, a fuse provided with a flanged head mounted in said shell-body beneath said screw-cap, and removable longitudinally therefrom, and a washer of leather or similar material held firmly beneath said flange and preventing the sifting of fine powder past said flange, substantially as described.

3. In an explosive shell, the combination with the shell-body, of a screw-cap held thereon, a fuse provided with a flanged head mounted in said shell-body beneath said screw-cap, and removable longitudinally therefrom, with means for holding said fuse against turning in said shell-body, and a washer of leather or similar material held firmly beneath said flange and preventing the sifting of fine powder past said flange, substantially as described.

4. In an explosive shell, the combination with the shell-body, of a screw-cap held thereon, a fuse provided with a flanged head, mounted in said shell-body beneath said screw-cap, and removable longitudinally therefrom, with a spline-pin locking said fuse against turning in said shell-body and held in place by said screw-cap, and a washer of leather or similar material held firmly beneath said flange and preventing the sifting of fine powder past said flange, substantially as described.

5. In an explosive shell, the combination with the shell-body, of a screw-cap held thereon, and a fuse mounted to slide axially in said shell-body and normally held beneath said screw-cap, with means for holding said fuse against turning in said shell-body, substantially as described.

In testimony whereof I affix my signature in presence of two witnesses.

LOUIS L. DRIGGS.
